Inventor:

Franklin A. Smith Jr.

by Crosby & Gregory, Atty.

UNITED STATES PATENT OFFICE.

FRANKLIN A. SMITH, JR., OF PROVIDENCE, RHODE ISLAND.

BUTTON-FASTENER.

SPECIFICATION forming part of Letters Patent No. 294,411, dated March 4, 1884.

Application filed December 17, 1883. (No model.)

To all whom it may concern:

Be it known that I, FRANKLIN A. SMITH, Jr., a citizen of the United States, and a resident of Providence, county of Providence, and State of Rhode Island, have invented an Improvement in Button-Fasteners, of which the following description, in connection with the accompanying drawings, is a specification, like letters on the drawings representing like parts.

My invention belongs to that class of sheet-metal button-fasteners which are adapted to hold buttons to shoes or other articles without the aid of a setting-instrument. Button-fasteners of the class mentioned are usually so constructed as to involve two bends in the metal blank to adapt it for use, or which necessitates one continuous bend in the tongue of the blank to form said tongue into a curvilinear or segmental loop or hook, so as to bring the end or point of the tongue or formed loop or hook adjacent to and opposite one side of the head bar or base. Button-fasteners involving two bends in their formation must be formed of comparatively thin, soft, and tender metal, and are much weakened by the sharp bends therein, while fasteners which are formed by giving a continuous bend to the tongue of the blank to form the curvilinear or segmental loop or hook are difficult of manufacture, and when so formed the end of the loop or hook is so disposed with relation to the other parts of the fastener that when it is endeavored to engage the hook with the eye of a shank-button it is found that the curve or bulge of said loop or hook engages the material of the shoe or other article before the end or point of the loop or hook can enter the shank-eye, thereby rendering the engagement of the fastener with a button a difficult matter.

My invention has for its object the formation of a button-fastener of the class designated which shall involve but one other than continuous bend in the tongue of the blank to form the loop or hook, and in which the end of the hook is so disposed with relation to the other parts thereof as to permit it to be readily passed into the shank-eye of a button in the act of securing a button to a shoe or other article.

To these ends my invention consists of a sheet-metal button-fastener having, essentially, a base and hook integral therewith, with the hook bent upon itself, and with its free end or that portion below the curvature or bend opposite to and substantially parallel with one side of the base, substantially as hereinafter described, and particularly pointed out in the claims.

Figure 1 is an elevation, and shows my improved button-fastener, enlarged, as holding a button to a piece of leather or other article. Fig. 2 is a plan of the blank from which my fastener is formed. Fig. 3 is an end view of my improved button-fastener. Fig. 4 is a rear view, and Fig. 5 is a front view, thereof.

My fastener is formed from the sheet-metal blank shown in Fig. 2, and consists of a base, *a*, and hook *b*. The hook projects from the cut edge *c* of the base *a*, and is curved or bent upon itself, as at *d*, with its free end or that portion below the curvature or bend opposite to and substantially parallel with one side of the base *a*, as shown in the drawings. By this disposition of parts the hook may be readily engaged with the shank-eye of a button, and be easily housed in the hole in the leather or other article, so as to bring the shank-eye of said button substantially above and at the outer surface of the leather. The point or extremity of the hook *b* is so disposed as to be substantially in the same plane with or slightly below the bottom line of the base *a*, the purpose of which is to prevent the free end of the hook *b* from being pulled through the hole in the leather and onto the outer surface thereof when strain is applied to the button and the hole becomes enlarged by wear. The strain or pull on the button being substantially at right angles to the base or somewhat in line with the leather or other material, the said strain causes the end of the hook *b* to press against the under side of the material at one side of the hole therein, while the base presses against the material at the opposite side of said hole. When under such strain, the fastener assumes a position somewhat in the line of strain or out of a perpendicular, which, it will be found, elevates the point or extremity of the hook partly above the base, 900

and were the point of the hook not carried to or slightly below the bottom line of said base it would soon be pulled out of the hole and onto the outer surface of the material upon the 5 enlargement by wear of the hole in said material.

My improved hook is cheap and of easy manufacture, and involves but one simple bend, given thereto by the die or former. As stated, 10 the hook can be quickly and easily inserted into the eye of a shank-button.

When it is desired to apply a button and fastener to a fabric or shoe, the shank of the button is pushed into a previously-made orifice in the fabric or leather of the shoe, so that 15 said shank will project from the under side of the material, when the point or extremity of the hook is passed into the shank-eye until the bend of the hook engages the said shank-eye, 20 whereupon a pull is given to the button to cause the hook to be drawn up into the orifice, substantially as indicated in Fig. 1.

What I claim is—

1. A sheet-metal button-fastener consisting 25 of the base and the hook integral therewith,

the said hook projecting from the cut edge *c* of the base, and having the semicircular bend *d* and straight free end below the said bend *d*, the said straight free end being substantially parallel with the post of the hook below the 30 said curve and with the base, the point or extremity of the hook passing beyond the upper cut edge, *c*, of the base, substantially as shown and described, and for the purpose set forth.

2. The herein-described one-piece sheet-metal button-fastener, consisting, essentially, of the base *a* and hook *b*, the said hook projecting from the cut edge *c* of the base and bent upon itself, with its free end opposite to and substantially parallel with one side of the 40 base *a*, and its point or extremity slightly below the bottom line of said base *a*, all as shown and described, and for the purposes set forth.

In testimony whereof I have signed my name to this specification in the presence of two sub- 45 scribing witnesses.

FRANKLIN A. SMITH, JR.
